DESIGN FOR A WINCH

Harry Knutson, St. Paul, Minn., assignor to American Hoist & Derrick Co., St. Paul, Minn., a corporation of Delaware

Application January 29, 1945, Serial No. 117,661

Term of patent 14 years

(Cl. D41—1)

To all whom it may concern:

Be it known that I, Harry Knutson, a citizen of the United States, residing at St. Paul, in the county of Ramsey and State of Minnesota, have invented a new, original, and ornamental Design for a Winch, of which the following is a specification, reference being had to the accompanying drawings, forming part thereof.

Fig. 1 is a top plan view of a winch disclosing my new design;

Fig. 2 is an end elevational view;

Fig. 3 is an end elevational view disclosing the end of the winch opposite that shown in Fig. 2;

Fig. 4 is a side elevational view; and

Fig. 5 is a side elevational view disclosing the side of the winch opposite that shown in Fig. 4.

I claim:

The ornamental design for a winch, as shown.

HARRY KNUTSON.
